APRON

Georgia I. Camp, Palo Alto, Calif.

Application July 6, 1954, Serial No. 31,294

Term of patent 14 years

(Cl. D3—26)

Fig. 1.

Fig. 2.

Fig. 3.

Fig. 1 is a developed view of an apron showing my new design, the Shirred waistband being stretched to its maximum position and the tie strings broken away for convenience of illustration;

Fig. 2 is a fragmentary view of the apron shown in Fig. 1 with the waistband in its normal Shirred position; and

Fig. 3 is an enlarged fragmentary view of the apron shown in Fig. 1, illustrating one of the applique patches in detail.

The characteristic feature of my design resides in the contrastingly colored, rick-rack trimmed appliques applied to the skirt in the manner shown.

I claim:

The ornamental design for an apron as shown and described.
